UNITED STATES PATENT OFFICE.

ALFORD PERVIS WILLOUGHBY, OF OLNEY, TEXAS, ASSIGNOR OF ONE-HALF TO
WILLIAM D. BOLDING, OF OLNEY, TEXAS.

COLLAPSIBLE COOP.

1,151,844.

Specification of Letters Patent. Patented Aug. 31, 1915.

Application filed June 12, 1914. Serial No. 844,677.

To all whom it may concern:

Be it known that I, ALFORD PERVIS WILLOUGHBY, a citizen of the United States, residing at Olney, in the county of Young 5 and State of Texas, have invented a new and useful Collapsible Coop; and I do hereby declare the following to be a full, clear, and exact description of the invention, such as will enable others skilled in the art to which 10 it appertains to make and use the same.

This invention relates to a new and useful collapsible chicken coop.

An object of the invention is to provide an improved coop of this nature having a skeleton top and provided with collapsible side 15 and end pieces, the said top having guides to receive lateral projections of the side pieces; to not only guide the side pieces when collapsing, but also guide the top.

Another object of the invention is to provide a collapsible chicken coop comprising simple and efficient and practical features of 20 construction.

In practical fields the details of construction may necessitate alterations, falling within the scope of what is claimed.

The invention comprises further features and combination of parts, as hereinafter set forth; shown in the drawings and claimed:

In the drawings: Figure 1 is a plan view of the improved coop constructed in accordance with the invention. Fig. 2 is a side view. Fig. 3 is an end view. Fig. 4 is a sectional view on line 4—4 of Fig. 1. Fig. 5 is a transverse sectional view showing the coop collapsed. Fig. 6 is a longitudinal sectional view showing the coop collapsed. Fig. 7 is a side view of another form of coop. Fig. 8 is an end view. Fig. 9 is a transverse 30 sectional view showing the coop collapsed. Fig. 10 is a longitudinal sectional view showing the coop collapsed. Fig. 11 is a plan view of the coop shown in Fig. 7.

Referring to the drawings, 1 designates the base member, to which the side and end pieces 2 and 3 are hingedly connected by means of staples 4. It will be observed that the frames 5 of the side pieces are constructed of two pieces of wire material, one piece 6 forms the bottom rail of the frame of each side piece and portions of the end rails 7, while the other piece 8 forms the top rail 9 of each side piece, the portions 10 of the piece 8 are twisted about the end rails of the piece 6, as shown. The extremities of

the end rails of the piece 6 are extended laterally and designated by the numeral 11, and operable in guides 12 of the top 13, thereby not only guiding the top when the same is collapsed, but also guiding the side 60 pieces. The lower rail of the piece 6 of each side is formed in loops as shown at 14 extending laterally from the side, to contact with the base 1 when the side is in a vertical position. The sides are provided with longitudinal and vertical wires 15 and 16.

The top is constructed with a rectangular shaped frame; the longitudinal and transverse portions 17 and 18 of which are hooked together as shown at 19. The longitudinal 70 portions 17 are braced and reinforced by the rods or wire parts 20. Extending longitudinally and transversely and substantially centrally of the top and intersecting are bracing and reinforcing members 21 and 22 linked together as at 23 where they intersect. These members 21 and 22 consist of twisted wire, which merge into and form parts of the rectangular frame of the top. The rectangular frame of the top is provided with additional longitudinal and transverse wires 24 and 25, thereby forming a mesh-work cover or top, which is provided with an opening 26 and a closure 27 therefor hinged at 28, there being a sliding bar 28^a 80 to secure the closure in a locked position. The end pieces are constructed of single lengths of wire, to form their rectangular frames; the end portions of these lengths of wire are twisted together, as shown at 28. 90 The lower rails of the end pieces 3 are hingedly connected to the base 1 by the staples 30, and are formed into laterally-extending loops 31 to engage the base 1 to limit the end pieces in their vertical position. 95 The frames of the end pieces 3 are provided with longitudinal and transverse wires 32 and 33. Angular wire latches 34 are hingedly connected to the top as shown at 36. Each latch is so constructed, as to arch or straddle the longitudinal central reinforcing or bracing member, so as to act as abutments to hold the upper rails of the end pieces 3 against the inner portions of the guides of the side pieces, thereby not only holding the end pieces vertically, but at the same time holding the entire structure of coop rigid or firm. The side portions of the latches may be bent toward each other, to hold them in position. 100 105 110

Referring to Figs. 7 to 10 inclusive it will be observed that the side and end pieces are constructed of rectangular wood frames having longitudinal and transverse wires 5 36 and 37. The wood frames 38 are hingedly connected to the base 1 as shown at 39. In these figures as well as in Figs. 1 to 6 inclusive, the end pieces swing or collapse between the side pieces, and the side pieces 10 collapse inwardly and upon the end pieces. Also in Figs. 7 to 10 inclusive the top is constructed of a rectangular wood frame having longitudinal and transverse wires 40 and 41, which are so arranged as to form an 15 opening 42 through which the fowl may be inserted into the coop, there being suitable hinged closure 44 and a slide bar to hold the same closed, the slide bar being designated by the numeral 45. The side and end rails 20 47 and 48 of the rectangular frame 49 of the top extend down far enough to be engaged by the sides and ends of the coop. The sides of the coop in Figs. 7 to 10 inclusive have laterally extending wire projections 50 25 extending through the slot 51 of the end portions of the top, thereby not only guiding the top and end pieces relative to each other when the coop is being collapsed, but also anchoring the top to the end pieces. Pivoted to two of the transverse wires of the 30 top in Figs. 7 to 10 are latches 52 similarly constructed to the latches hereinbefore referred to and performing the same functions.

35 In all the figures of the drawing the longitudinal portions or rails of the top of the coop are provided with hingedly connected hooks 54, to engage eyes 55 of the base to hold the several parts of the coop in their 40 collapsed form.

The invention having been set forth, what is claimed as new and useful is:—

45 1. A collapsible coop comprising a base member, side, end and top pieces constructed of wire rectangular frames having longitudinal and transverse wires, said side and end pieces being hingedly connected to the base, the sides being constructed of two pieces of wire having their end portions twisted together, the extremities of one of the wire 50 pieces of each side being extended laterally,

the top piece having reinforcing means and end guides to receive the lateral extremities of the side pieces, to guide the side and top pieces relative to each other when collapsing or distending the coop structure, the end pieces being adapted to collapse inwardly between the side pieces, and the side pieces upon the end pieces, said top having wire latches hingedly connected thereto and adapted to arch one of the reinforcing means of the top and assume positions in the path of the end pieces to hold the same against the inner portions of the guides to hold the structure erect and rigid, the opposite sides 65 of the latches being forced together to lock them in place.

2. A collapsible coop comprising a base member, side, end and top pieces constructed of wire rectangular frames having longitudinal and transverse wires, said side and end pieces being hingedly connected to the base, the sides being constructed of two pieces of wire having their end portions twisted together, the extremities of one of the wire pieces of each side being extended laterally, the top piece having reinforcing means and end guides to receive the lateral extremities of the side pieces, to guide the side and top pieces relative to each other when collapsing or distending the coop structure, the end pieces being adapted to collapse inwardly between the side pieces, and the side pieces upon the end pieces, said top having wire latches hingedly connected thereto and adapted to arch one of the reinforcing means of the top and assume positions in the path of the end pieces to hold the same against the inner portions of the guides to hold the structure erect and rigid, the opposite sides 75 of the latches being forced together to lock them in place, the lower rails of the side and end pieces having laterally extending loops to engage the base to hold the side and end pieces erect.

90 In testimony whereof I have signed my name to this specification in the presence of two subscribing witnesses.

95 ALFORD PERVIS WILLOUGHBY.
